RECOIL MECHANISM

Victor F. Lucht, Washington, D. C.

Application June 18, 1942, Serial No. 447,520

3 Claims. (Cl. 89—43)

(Granted under the act of March 3, 1883, as
amended April 30, 1928; 370 O. G. 757)

The invention described herein may be manufactured and used by or for the Government for governmental purposes, without the payment to me of any royalty thereon.

An object of this invention is to provide a novel arrangement of apparatus for controlling the movement of gun parts in recoil and/or counterrecoil.

Another object of this invention is to provide an improved structure for mounting a recoil spring coaxially with a gun barrel.

Another object of this invention is to provide a gun recoil cylinder coaxially mounted around a gun barrel.

Another object of this invention is to provide a light and compact recoil mechanism especially designed for mounting in an airplane wherein space and weight requirements are exacting.

Another object of this invention is to provide a gun barrel having a recoil cylinder coaxially mounted thereon with fluid tight packing adapted to withstand the rather high temperature in the vicinity of the gun barrel.

Another object of this invention is to provide a recoil mechanism for a gun having relatively short fluid flow passages.

The specific nature of the invention as well as other objects and advantages thereof will clearly appear from a description of a preferred embodiment as shown in the accompanying drawings in which:

Figure 1 is a central cross sectional view and shows the position of the parts of the recoil and buffer mechanisms in their normal position with the barrel B at one end of its operating stroke.

Figure 2 is a central cross sectional view and shows the position of the parts of the recoil and buffer mechanisms when the barrel B is at the other end of its operating stroke.

Figure 3 is a central cross sectional view and shows the position of the parts of the recoil and buffer mechanisms in one position of the barrel B as it returns from the position shown in Figure 2 to the position shown in Figure 1 and said one position lies in a region defined by limits MN wherein buffer action effecting movement of barrel B is predominant.

Figure 4 is a sectional view taken substantially on line 4—4 of Fig. 3.

Figure 5 is a sectional view taken substantially on line 6—6 of Fig. 3.

Figure 6 is a sectional view taken substantially on line 6—6 of Fig. 3.

Figure 7 is an enlarged view of the elements shown in the upper right hand corner of Fig. 1.

Essential elements of my invention comprise support cylinder A, barrel B, piston cylinder C, sleeve D, cradle tube E and recoil spring F. A pressure responsive valve having general reference numeral G is carried by the piston cylinder C.

The barrel B is adapted to slide relative to aluminum support cylinder A carrying spaced annular aluminum bronze bearing members 10, 11, 12, 13, 14, 15, 16 for providing a good wearing surface between barrel B and support cylinder A. The aluminum bronze bearing members 10, 11, 12, 13, 14, 15, 16 are conveniently fastened to the support cylinder A by means of tongue and groove connections but it is apparent that the bearing members may be fastened to the support cylinder A by other means, for instance, by a screw-threaded connection.

It is noted that the support cylinder A has, at 20 its downward end in Figure 1, an annular L-cross sectional shaped flange 17 having internal screw threads 17a thereon and has, at its upper end in Figure 1, a screw-threaded portion 16a for attachment of recoil mechanism inclosing structure as will be seen later. A second support cylinder annular flange 18 having four equally spaced fastening holes 18a therethrough is formed integral with flange 17; and, the cylindrical structure produced by flange 18 is 30 adapted to receive a fastening implement (not shown) by which the cradle tube or support cylinder A is fastened to support cylinder E. Holes 18a are adapted to receive projections on said implement.

Cylinder piston C of steel is fastened to barrel B by means of the cooperating nut 19 and connector 20 which are each screw-threaded to the cylinder piston C and barrel B respectively and hence cylinder piston C has the same motion as barrel B. Cylinder piston C snugly surrounds support cylinder A and slides thereon as the barrel B moves due to recoil and/or counterrecoil forces.

The stationary cradle cylinder E having sleeve D snugly and fixedly mounted therein and having screw threads 20a engaging support cylinder screw threads 17a is closed at its upper end in Figure 1 by means of screw-threaded follower 21 which engages cradle cylinder threaded portion 20b. Screw threaded annular follower 21 (Fig. 7) is adapted to adjustably tension annular packing 22, 23 between bottom annular adapter 24 and annular movable gland 25; top adapter 26 separates packing 22 from packing 23 and also

conforms to the contour of packing 22 as does bottom adapted 24.

The packing 22 is of the type well known in the art and comprises essentially a series of annular dished members 22a (Fig. 7) each made of relatively soft fabric material having a flexible center ring core 22b for flexibility. Four of such annular dished members 22a are disclosed in Figure 7 but it is apparent that other means similar to dished members 22a are readily suggested by one skilled in the art for providing a fluid tight connection between stationary cradle tube E and movable cylinder piston C.

Also, cradle tube E is formed with an internal annular shoulder 20c (Fig. 7) which is recessed so as to hold annular bushing 21, preferably of hardened phosphor bronze so as to provide a suitable wear resistant stationary spring seat for recoil spring F. The other end of spring F is normally biased against annular shoulder 28a (Fig. 1) on piston cylinder C so as to normally press the piston cylinder C and attached gun barrel B downward to the position shown in Fig. 1.

From the structure thus far described it should be obvious that the gun barrel B and associated cylinder piston C both recoil due to firing of the associated gun, and thereafter the gun barrel B and associated cylinder piston C return to normal position under the influence of tensioned recoil spring F.

The annular space between cylinder piston C and support cylinder A at their upper ends in Figs. 1 and 7 is made tight by the following expedient: annular packings 29, 30 separated by gland 31 and adapted to conform to the abutting surfaces of annular support cylinder shoulder 32 and annular gland 33 respectively is compressed by screwing screw-threaded follower 34 on cooperating support cylinder screw threaded portion 35.

Sleeve D (Fig. 2) having a cut-out fluid orifice or slotted passage 36 of predetermined dimensions as will be described later is maintained in fixed relationship to cradle tube E by means of filling screw plugs 37 which extend into sleeve circular hole 38 and is held by cradle tube tapped portion 39.

In the recoil oil filling operation screw-threaded plugs 37, 40 are removed and recoil oil is circulated into cradle tube opening 41 and out of cradle tube opening 42 (Fig. 1) until the circulated oil flows uniformly without discontinuity due to entrapped air in the composite recoil cylinder. The recoil cylinder for confining the recoil cylinder oil or similar fluid is defined by support cylinder A, cradle tube E and the fluid tight connection comprising packing 22, 23.

The cylinder piston C carries the pressure responsive valve assembly G on the left hand end thereof in Fig. 5. The valve assembly G comprises the following essential elements: annular bracket 43 threaded on the end of cylinder piston C, annular valve casing 44 slidably mounted on cylinder piston C, valve guides 45 screw-threadedly mounted on valve casing 44 and cooperating with the bracket guide holes 43a, valve body 46 snugly received by the valve casing hollow portion 44a, screw-threaded plug 47 for holding valve body 46 in the valve casing hollow portion 44a by engaging a flange 46e on the valve body, and a spring 48 for normally biasing the valve body opening 46a in alignment with valve casing opening 44b. It will be observed, best from Fig. 4, that the guide pins 45 and valve bodies 46 are

alternately placed about the annular valve casing 44. The valve casing 44 besides forming a valve seat for valve body 46 also cooperates with cylinder piston projection or piston head 70 for blocking fluid flow through openings 70a in the cylinder piston head 70 when the barrel B and associated cylinder piston C returns in counter-recoil; in recoil, valve casing 44, due to fluid pressure, is moved against bracket 43 thus allowing recoil fluid to flow through the cylinder piston head openings 70a. In counterrecoil the valve casing 44 moves against cylinder piston head 70 and blocks fluid flow through cylinder piston projection openings 70a and substantially all the fluid flow in the vicinity of head 70 occurs through valve body opening 46a; however, fluid pressure acting on valve body wall 46d causes movement of valve body 46 against the action of spring 48 and tends to close port 44b thus causing the barrel B to return in counterrecoil with limited velocity in the region defined by the limits M—N (Fig. 1).

It is noted that the cylinder piston C carries two spaced annular projections or heads 70, 71 each having outer bearing surfaces adapted to make close sliding contact with the sleeve D which has two diametrically opposite throttle openings 36 therethrough (Fig. 4). Sleeve openings 36 are designed to offer resistance to fluid flow in a degree depending upon the position of cylinder piston C whereby the cylinder piston C and barrel B travel with substantially variable velocity notwithstanding that substantially constant propelling forces are exerted on the barrel B. It is also noted that due to the spacing of cylinder annular heads 70, 71 with respect to sleeve D correspondingly different size orifices are formed at the sleeve where those annular projections contact the sleeve.

In order to understand the controlling forces exerted on cylinder piston C in its movement one important fact must be understood, namely, that on recoil the sleeve aperture formed by the co-operation of cylinder piston head 71 will be controlling since the braking effect of the other annular projection is made ineffective due to the large holes 70a uncovered when the valve casing 44 is moved to the left in Fig. 5; and that on counter recoil in the range defined by M, N shown on Fig. 1 the aperture formed by annular piston head 70 with sleeve D is of small relative size so as to be controlling, and the fluid pressure on the left hand side of the head 70 in Fig. 5 will cause valve body 46 to move to the right to further limit the fluid flow through port 44b and further retard the movement of the cylinder piston C in counterrecoil.

In carrying out one recoil and counterrecoil stroke it is noted that both valve casing 44 and valve body 46 each individually serve as a valve body for the control of fluid flow.

Resilient disc 80 of leather or similar material fastened to nut 19 as by means of screws 80a serves to absorb some of the shock between the cradle tube and barrel when it returns to normal position (Fig. 1) at the end of the counterrecoil stroke.

Operation.—In the recoil of the gun, the parts being in the position shown in Figure 1, the braking fluid to the right of the valved piston 70 will pass freely through said piston and through the ports 46a in the valve 46, and 44a in valve casing 44, which ports are now in registry. At the beginning of this stroke pressure of the oil against the right end of the valve casing 44 causes the

same to move slightly to the left against the pressure of spring 48, and away from the piston 70 thus providing a space between said piston and casing to permit fluid to pass freely through the opening 70a of the piston 70. During this movement of the valve casing 44, the ports 46a and 44b remain in registry. Upon counterrecoil the reaction of the spring 48 forces the valve casing 44 against the piston 70 closing the opening 70a. The pressure to the left of the valve 46 will cause it to move back into its casing 44 against the pressure of spring 48 and close the ports 46a and 44b and prevent the passage of oil therethrough. When the gun reaches battery position the spring 48 will return valve 46 to normal position with ports 46a and 44b again in registry preparatory to the repetition of the cycle. In normal or battery position, as shown in Figure 1, the valved recoil piston 71 occupies the position N. In this position the left end of the passage 36, from N to M does not function during recoil stroke, but only that portion of the passage from N to the tapered right end. Valved piston 70 resists somewhat the counterrecoil movement of the gun by reason of the closing of the valve 46 but this does not interfere with the operation of the piston 71 during counterrecoil until piston 70 reaches position N in Figure 3, that is to say, at the point of the passage 36 where it left end begins to taper off. During the last part of the counterrecoil or from about point N to M, piston 70, (the valves of which are closed during counterrecoil), meets with increasing resistance due to the decreasing taper of the left end of the slotted passage 36. The valved piston 70 thus provides a buffer action at the end of the counterrecoil stroke of the gun.

I claim:

1. In a recoil and counter-recoil apparatus for a gun barrel, the combination of a gun barrel, a stationary tubular supporting member provided with internal bearing surfaces for the said gun barrel, a tubular member mounted for sliding movement on the external surface of the said tubular supporting member, the said tubular sliding member and the said gun barrel being secured together at one end thereof to move in unison, a second stationary tubular member surrounding the said tubular sliding member and spaced therefrom to provide an annular fluid space, a recoil spring within the said annular space, and a piston on the said tubular sliding member in sliding engagement with the internal surface of the second said tubular member.

2. In a recoil and counter-recoil apparatus for a gun barrel, the combination of a gun barrel, a stationary tubular supporting member provided with internal bearing surfaces for the said gun barrel, a tubular member mounted for sliding movement on the external surface of the said tubular supporting member, the said tubular sliding member and the said gun barrel being secured together at one end thereof to move in unison, a second stationary tubular member surrounding the said tubular sliding member and spaced therefrom to provide an annular fluid space, a recoil spring within the said annular space, and a pair of pistons on the said tubular sliding member in sliding engagement with the internal surface of the second said tubular member, one of the said pair of pistons being provided with valves.
3. In a recoil and counter-recoil apparatus for a gun barrel, the combination of a gun barrel, stationary tubular supporting member provided with internal bearing surfaces for the said gun barrel, a tubular member mounted for sliding movement on the external surface of the said tubular supporting member, the said tubular sliding member and the said gun barrel being secured together at one end thereof to move in unison, a second stationary tubular member surrounding the said tubular sliding member and spaced therefrom to provide an annular fluid space, a recoil spring within the said annular space, the second said tubular member being provided in its internal surface with a slotted passage having a maximum central opening and tapering toward the breech end of the barrel and toward the muzzle end thereof, and a pair of pistons on the said tubular sliding member in sliding engagement with the internal surface of the second said tubular member, one of the said pistons being, in the battery position of the said connected barrel and tubular sliding member, substantially at the juncture between the said maximum central portion and the said tapered breech end portion of the slotted passage, and the other of the said pistons being substantially at the end point of the said tapered end portion, the last said piston being provided with valves adapted to be closed during the counter-recoil stroke whereby the said valved piston cooperates with the said tapered breech end portion of the slotted passage to buffer the last portion of the said counter-recoil stroke.

VICTOR F. LUCHT.
